(57) **CLAIM**

The ornamental design for an interior panel for a vehicle, as shown and described.

DESCRIPTION

FIG. 1 is a front left perspective view of an interior panel for a vehicle according to the present invention.

FIG. 2 is a front right perspective view of the interior panel for a vehicle shown in FIG. 1.

FIG. 3 is a rear right perspective view thereof.

FIG. 4 is a rear left perspective view thereof.

FIG. 5 is a front and right view thereof.

FIG. 6 is a front view thereof.

FIG. 7 is a rear view thereof.

FIG. 8 is a left side view thereof.

FIG. 9 is a right side view thereof.

FIG. 10 is a top view thereof.

FIG. 11 is a front right perspective view of the interior panel for a vehicle shown in FIG. 1, along with an accompanying center console, with the armrest of the center console moved forward and the screen deployed; and,

FIG. 12 is a front and right view of the center console shown in FIG. 11.
